UNITED STATES PATENT OFFICE.

JOHN LETH-ESPENSEN, OF DETROIT, MICHIGAN.

BAG HOLDER.

Application filed February 5, 1927. Serial No. 166,164.

This invention relates to improvements in bag holders and its object is to provide means for supporting or holding a bag open to permit filling it in a convenient manner.

With the foregoing and other objects in view the invention consists in the combination and arrangement of parts to be herein-after fully described, particularly pointed out in the appended claims and illustrated in the accompanying drawing which forms a part of this application and in which—

Fig. 1 is a top plan view of the bag holder.

Fig. 2 is a view of the bag holder in side elevation.

Fig. 3 is an enlarged cross sectional view taken on line 3—3 of Fig. 1.

Like reference characters denote corresponding parts throughout the several views.

The bag holder comprises a hopper-like body to which a pair of oppositely disposed handles are fulcrumed, said handles at their lower ends carrying a pair of curved bag-engaging bars that serve automatically to support the bag in open position when the device is held by its handles.

The hopper-like body 1 tapers from its mouth 2 to its discharge end 3 and is preferably oblong in shape and formed at its ends with ears 4 arranged in pairs. The members of each pair of ears are connected together by a bolt 5 and an angular handle 6 is fulcrumed upon said bolt, said handle comprising a hand grip 7 at its upper end, said handle being integral with a curved bar 8 formed at the handle end remote from the hand grip 7. The bars 8 are disposed opposite or contiguous to the body 1 and the shape of each handle is such that as the

weight of the bag holder is supported from the hand grips 7 the bars 8 are caused to move away from the body 1.

The lower end of the body 1 and the bars 8 are placed inside the mouth of the empty bag 9 to be supported. The bag holder is then supported by the hand grips 7 causing the bars 8 to stretch the mouth of the bag thus holding it suspended in open position. The bag is now readily filled by introducing the material into the hopper-like body. When the bag is filled the hand grips are released or pressed outwardly from each other thus causing the bars 8 to move toward the body 1 and release the bag.

What is claimed is:—

1. In a bag holder, a hopper-like body portion, ears arranged in pairs disposed opposite each other and formed integral with said body portion, handles fulcrumed to said ears, and curved bars integral with said handles and disposed upon the opposite side of the fulcrums with relation to said handles.

2. In a bag holder, a hopper-like body portion, ears formed upon said body portion, bolts connecting said ears in pairs, angular handles fulcrumed upon said bolts, hand grips at one end of said handles and disposed above said body portion, and curved bars integral with said handles contiguous to said body portion, said bars being disposed upon the opposite side of the fulcrums with relation to said handles.

In testimony that I claim the foregoing as my own I have hereto affixed my signature.

JOHN LETH-ESPENSEN.
